UNITED STATES PATENT OFFICE.

WILLIE F. WALL, OF WATSONVILLE, CALIFORNIA.

COMBINED EXPANSION AND COUNTERBORING BIT.

1,425,300.

Specification of Letters Patent. Patented Aug. 8, 1922.

Application filed January 25, 1921. Serial No. 439,790.

To all whom it may concern:

Be it known that I, WILLIE F. WALL, a citizen of the United States, residing in the city of Watsonville and county of Santa Cruz and State of California, P. O. Box 153, have invented a new and useful Improvement in a Combined Expansion and Counterboring Bit, of which the following is a specification.

10 My invention relates to improvements in combined expansion and counterboring bits of the type disclosed in my copending application filed October 29th, 1920; Serial No. 420,456, reference to which is hereby made.

15 The present invention consists of providing a longitudinally disposed groove upon the head of the tool within which the cutting bits are adjustably mounted, the object being to provide a greater range of 20 adjustment of said bit longitudinally upon the tool.

I accomplish these and other objects by means of the improved form disclosed in the drawings forming a part of the present 25 specification wherein like characters of reference are used to designate similar parts throughout the said specification and drawings, and in which:—

Fig. 1 is a broken front elevation of my 30 invention, one cutter blade being in position to adapt the bit for boring holes;

Fig. 2 is a similar view, disclosing another cutter blade in position for counterboring a hole;

35 Fig. 3 is a broken side elevation of Fig. 1 with the lower cutter blade removed; and

Fig. 4 is an enlarged transverse sectional view taken on line 4—4 of Fig. 3 in the direction indicated.

40 Fig. 5 is a rear view of one of the cutter blades;

Referring to the drawings the numeral 10 is used to designate the shank of the bit and 45 11 the head comprising an upper semi-cylindrical portion 12 and a lower semi-conical portion 13. The flat sides of the portions 12 and 13 lie in the same plane as the axis of the bit or the shank 10 and are provided with lateral and longitudinal serrations 16 throughout the entire surface of 50 said flat sides, the purpose of which will hereinafter be more fully set forth.

A lead screw 14 and a cutting flange 15 are provided on the lower or apex end of 55 the semi-conical portion 13 to facilitate en-

trance and boring of the tool into the material to be operated upon.

In place of the clamp 19 disclosed in my copending application hereinbefore referred to the head 11 is provided with a co-axial 60 dove-tailed groove 17 having an enlarged opening 19 at the upper end thereof to facilitate the introduction of a head 20 slidably mounted within said groove 17 and arranged for longitudinal movement only within said 65 groove 17 to provide axial adjustment for either one of a pair of longitudinally slotted cutter blades 21.

The cutter blade 21 is provided with a substantially horizontal cutting portion 25, 70 as in my copending application above referred to, which will cut away the wood in a substantially horizontal plane within the limits of the scoring lip on the cutter as shown in the drawings. Fig. 1 shows the 75 shorter cutting lip in operative position operating as an expansion bit, while Fig. 2 shows the upper longer cutter blade in operative position as a counterbore. As the tool is rotated the horizontal cutting edge 25 80 cuts away the wood immediately thereunder as shown. As a counterbore, the tapered portion of the head is positioned in a previously bored hole, and the cutter adjusted longitudinally to intersect the tapered edge 85 of the head at the point of engagement with the hole, and adjusted laterally to give the desired diameter of counterbore. The tapered portion may thus be fitted to any hole 90 as a centering means whereby said hole may be counterbored or enlarged upon the original axis.

A suitable screw 22 extends through the slot in its respective cutter blade 21 and is threaded or screwed into the head 20 so 95 that when said screw is tightened said head 20 will be clamped tightly against the angular sides of the groove 17 and the adjacent face of the cutter blade 21, which is also serrated longitudinally and laterally, as at 100 25, as disclosed in Fig. 5 of the drawings, is tightly clamped against the serrated surface of the head 11, thereby preventing movement of said cutter blade 21 relatively to the head 11 while the tool is in operation. 105

By means of this novel sliding arrangement a greater range of adjustability of the cutter blades 21 may be provided as the said blades 21 may be moved axially and longitudinally of the head 11 in infinite de- 110

gree which is only limited by the distance between the longitudinal and lateral serrations 16.

As these serrations 16 are longitudinally and laterally disposed as well as the serrations on the rear sides of the cutter blades 21 it is obvious that the said blades 21 are effectively held against movement by the engagement of said serrations when the 10 screw 22 is tightened.

Reduction to practice has disclosed that the clamps 19 disclosed in my copending application referred to must be made considerably larger than disclosed in said application. The provision of the slot 17 therefore has eliminated the use of cumbersome and expensive parts which materially limited the range of adjustment.

It is obvious from the foregoing that I 20 have provided an improved and simplified form of construction whereby a greater range of adjustability may be obtained with fewer parts.

Having thus described my invention what 25 I claim as new and desire to secure by Letters Patent is:—

1. A combined expansion and counterboring bit comprising a semi-conical head provided with a lead screw and a cutting 30 flange; and having a longitudinal groove disposed along the axis of the head; a cutter blade; and means operatively connected to the blade and slidably engaging the slot whereby said cutter blade may be adjusted 35 longitudinally and radially.

2. A combined expansion and counterboring bit comprising a head having a lower semi-conical and an upper semi-cylindrical portion and provided at the lower end of 40 the semi-conical portion with a lead screw and a cutting flange, the flat sides of said semi-cylindrical and semi-conical portions lying in the plane of the axis of said bit

and having a groove longitudinally disposed thereon along the axis of the head; a cutter 45 blade; and means slidably mounted within the groove for adjustably connecting the cutter blade to the flat side of said head to permit longitudinal and radial adjustment.

3. A combined expansion and counterboring bit comprising a semi-conical head provided with a lead screw and a cutting flange and having a groove formed longitudinally along the axis upon the flat side of said head; a nut mounted slidably for 55 longitudinal movement only within said groove; and a cutter blade detachably and slidably connected to said nut to provide axial and radial adjustment of said blade.

4. A combined expansion and counterboring bit comprising a semi-conical head having a lead screw and a cutting flange and a dove-tailed groove arranged within said head and along the axis of the bit, a nut slidably mounted for longitudinal 60 movement only within said slot; a longitudinally slotted cutter blade; and means for engaging the slot in the cutter blade and the nut for longitudinal and radial adjustment of said blade.

5. A combined expansion and counterboring bit comprising a semi-conical head having a lead screw and a cutting flange and likewise provided with a groove longitudinally disposed along the axis, said groove 75 having an enlarged end for the introduction of a nut; a nut slidably mounted within the slot; a longitudinally slotted cutter blade radially positioned on said head; and means for slidably engaging the cutter blade 80 slot and detachably connecting said blade with said nut for longitudinal and radial adjustment of said blade.

In witness whereof I hereunto set my signature.

WILLIE F. WALL.
